GOVERNOR

John W. Bembry, Unadilla, Ga.

Application July 1, 1935, Serial No. 29,341

2 Claims. (Cl. 264—15)

This invention relates to a governor mainly designed for controlling the speed of an internal combustion engine, the general object of the invention being to provide a governor which is very sensitive and which can be manufactured to sell at low cost and which can easily be repaired when damaged.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a top plan view of the governor showing it in use for controlling the speed of an internal combustion engine.

Figure 2 is a side view of the governor with parts in section.

Figure 3 is a longitudinal sectional view through the front part of the governor and showing how the same is connected to the lever.

Figure 4 is a section on the line 4—4 of Figure 1.

Figure 5 is a section on the line 5—5 of Figure 2.

Figure 6 is a section on the line 6—6 of Figure 1.

Figure 7 is a fragmentary view looking toward the front of the governor.

In these drawings, the numeral 10 indicates the shaft of the governor which has its inner or rear end threaded into a shaft 11 of the motor M, the forward end of the shaft 10 being of rectangular shape in cross section as shown at 10' and this part has a sliding fit in a socket 12, of similar shape in cross section, in a member 13. A strap 14 of leather or the like has a hole in its central portion through which the inner portion of the shaft 10 passes and this hole carrying part 14 of the strap is held on the shaft by the nuts 16 and 15 threaded on the shaft with a washer 17 passing between the hole carrying part of the strap and the nut 15 as shown in Figure 5. The nut 14 is of rectangular shape so that the two portions of the strap or strip extending from the part carrying the hole therein, will be caused to assume the parallel position shown in Figures 1, 3 and 5. The ends of the strap or strip are pressed around the enlarged part 13' at the inner end of the part 13 and a clamping band 17 is

passed around the two end portions 14', as shown in Figure 4 for fastening said end portions to said part 13'. A weight 18 is connected to each parallel portion of the strap by a bolt and nut shown generally at 19.

Thus it will be seen that when the shaft 10 is rotated by the shaft 11 at a predetermined speed the weights would swing outwardly and thus cause the parallel portions of the strap or strip to bow and thus exert a pull upon the member 13 which slides said member on the front end of the shaft 10.

This member 13 has a socket 20 in its front end for receiving the inner end of the pin 21, the pin being held in the socket by a cotter pin 15 22 and the pin 21 passes through a hole in a circular part 23 of a lever 24 which is pivoted at 25 to a leg 26 fastened to the front part of the motor. A longer leg 27 is fastened to the front part of the motor and has a slot 28 therein 20 through which the lever passes and this leg 27 has a bent part 29 at its front end for receiving the eye bolt 30 to which a spring 31 is connected which is also connected to the lever, this spring tending to hold the governor in extended position. A sectional long rod 32, the sections of which are connected together by a turnbuckle 33, is pivoted to the free end of the lever 24 and is adapted to be connected to the throttle valve of the motor so that the operation of the governor 30 will regulate the valve and thus keep the speed of the motor at the desired speed.

As before stated the use of the leather strap 14 as a part of the governor makes the governor inexpensive to manufacture and this strap can 35 be easily replaced by a new one when worn or damaged and the strap makes the governor very sensitive.

It is thought from the foregoing description that the advantages and novel features of the 40 invention will be readily apparent.

It is to be understood that changes may be made in the construction and in the combination and arrangement of the several parts, provided that such changes fall within the scope of the 45 appended claims.

What is claimed is:—

1. A governor of the class described comprising a shaft, a flexible strap of non-metallic material having a hole in its central portion through 50 which the shaft passes, nuts on the shaft for connecting said portion of the strap to the shaft, the other portions of the strap extending parallel to the shaft, a member slidably arranged on the shaft, a clamp for connecting the ends of the 55

strap to the sliding member, a lever, means for connecting an intermediate part of the lever to the sliding member, and spring means for holding the lever in a position with the sliding member in outward position with the parallel portions of the straps taut and means for connecting the lever to the member which is to be governed.

2. A governor of the class described comprising a shaft, a flexible strap having an opening in its central portion through which the shaft passes, nuts on the shaft for connecting said portion of the strap to the shaft, the other portions of the strap extending in parallel relation, a member slidably arranged on the shaft, a clamp

for connecting the ends of the strap to the sliding member, a lever, means for connecting an intermediate portion of the lever to the sliding member, an elongated arm anchored at one end and provided with a lateral portion at its free end disposed in the general longitudinal direction of the lever and having an opening therein, a rod disposed through the said opening of the lateral portion and being threaded and provided with a nut and a spring having one end connected to the threaded rod and the other end to the lever for holding the lever in a position with the sliding member in outward position.
